WILLIAM A. WEAVER, OF SHAKER HEIGHTS, OHIO

PACKAGE OF DENTAL SUPPLIES

Application filed March 8, 1929. Serial No. 345,386.

This invention relates to a package of dental supplies and has for its general object the provision of a compact and inexpensive package of this character having a container structure in which are supported, in proper spaced relation, a plurality of articles for dental use, such as a tube of tooth paste, a tooth brush, and a bottle of antiseptic solution, the construction of said container structure and the arrangement of said articles therein being such that the package can be handled, stored and mailed with the utmost safety to the contents thereof.

Further objects of the invention are in part obvious and in part will appear more in detail hereinafter.

In the accompanying drawing, Fig. 1 is a central vertical sectional view of the present improved package; Fig. 2 is a cross sectional view thereof on the line 2—2, Fig. 1; and Fig. 3 is an expanded view of the several parts of the package, some of said parts being in vertical or longitudinal section.

The present improved package includes a container structure in which are supported, in proper spaced relation, a plurality of articles for dental use, such as a tube of tooth paste, a tooth brush, and a bottle of antiseptic solution.

In the embodiment of the invention here illustrated, the container structure is in three parts and comprises two identical tubular container members A each having a closed end, and a tubular centering member B therefor, over which the two container members are telescoped or sleeved. The tubular body portions 1 of the two container members are preferably of cardboard of sufficient strength, due either to thickness or to quality of material, to give them the necessary rigidity and durability. The two end portions 3 of the container members, one for each, are preferably of sheet metal, such as tin, and have their rim portions secured to ends of the body portions 1, such as by crimping said rim portions thereabout, as at 5, which positions the circular closing parts of said end portions slightly within said body portions, as clearly indicated in the drawing. The tubular centering member B is a simple one-

piece tube, preferably of cardboard, substantially rigid in character and provided with a lining or inner coating of paraffin or other water proof material. The length of said tube is preferably about the same as, but never greater than, the combined depth of the two container members, which enables the edges of the open ends of said container members to be brought into abutting relation when the package is in made up condition, as indicated in Fig. 1.

The contents of the package are a plurality of articles for dental use, three in the present instance. They comprise an ordinary or standard tube C of tooth paste; a tooth brush D inclosed in a protecting paper cover E; and a bottle F of an antiseptic solution or the like, said bottle having the usual neck 7 and being of a size to snugly fit within the centering tube B.

As indicated in Fig. 1, the package is made up by bringing one half of the centering tube B and one of the container members A into telescoping relation, this container member therefore becoming the lower one. The bottle F is then arranged within said enclosed or lower part of the centering tube B, with its bottom in abutting relation with the end 3 of the lower container member and its neck extending toward the open or upper end of the centering tube B. The lower end portion of a spacing and supporting tube K, preferably of substantially rigid cardboard, is then sleeved over the neck 7 of said bottle, said tube resting upon the top portion 8 of said bottle and being of such size as to more or less snugly fit the neck thereof.

The tube C of tooth paste is then inserted into the spacing and supporting tube K, in inverted position, and is held in proper position within said tube by its permanently closed flat end 9, which is of greater length than the diameter of said spacing and supporting tube, so that said tooth paste tube end rests upon the upper edge of said spacing and supporting tube.

Into the annular chamber 12 between the spacing and supporting tube K and the centering tube B is placed the tooth brush D with its protecting cover E, the lower ends of

said brush and cover resting upon the top portion 8 of the bottle F. Additional tooth brushes, literature of various kinds and other objects may also be placed in said chamber, as will be readily understood.

5 The other container member A is then sleeved over the exposed or upper part of the centering tube B, and is moved down thereon until its lower edge abuts the upper edge of 10 the lower container member. This brings the circular closing part of the end portion 3 of the upper container member into firm engagement with the flat closed end 9 of the tooth paste tube C, which end is preferably 15 turned to one side, with the result that the upper end portion of the spacing and supporting tube K is not only maintained in concentric relation with respect to the centering tube B, but also the lower end portion thereof is held down against the top portion 8 of 20 the bottle F. Furthermore, such engagement serves to maintain the tooth paste tube C in proper position within the spacing and supporting tube K, although ordinarily, said 25 tooth paste tube and said spacing and supporting tube are of such relative size that there will be little space therebetween for lateral movement of the tooth paste tube. If desired, the parts may be so proportioned 30 that the lower or capped end 11 of the tooth paste tube C will engage the removable cork stopper 10 in the bottle neck 7, so that there can be no accidental loss of the contents of 35 the bottle F by the coming out of said stopper.

The package may be maintained in closed or made up condition by any suitable means, such as by one or more labels secured to the tubular outer surface of both the container 40 members A. One label, of a size to completely cover the tubular outer surfaces of both container members, is quite satisfactory, for it not only serves as a connecting means for the two container members, but also as a 45 wrapper or cover therefor.

50 While the container members A and the centering tube B are shown as of circular form in cross section, they might obviously be of non-circular form, such as square or hexagonal and the word "tubular" is to be construed as of sufficient breadth to include 55 all such arrangements. Other changes may also be made without departing from the spirit and the scope of the present invention, as will be readily understood.

60 Preferably a key 13 may be provided for use with the tube of tooth paste C, to facilitate the rolling up of the tube to completely expel its contents. This key may be assembled with the tube of tooth paste by means of a rubber band 15, which holds said key alongside the tooth paste tube, as indicated in Fig. 1.

65 What I claim is:

1. A package of dental supplies comprising

70 a substantially tubular container structure having upper and lower closed ends attached thereto, a bottle of liquid arranged within said container structure in abutting relation with the lower end thereof and having a neck extending toward the upper end thereof, a one-piece spacing and supporting tube arranged within said container structure in spaced relation to the side wall thereof and having its upper end portion terminating adjacent the upper closed end of said container structure and having its lower end portion resting on said bottle and telescoping its neck and being held against said bottle and in such telescopic relation by the upper end of said 75 container structure, and a tube of tooth paste arranged in and fitting said spacing and supporting tube between said bottle neck and the upper closed end of said container structure.

75 2. A package as set forth in claim 1, characterized in that the container structure includes two container parts and a centering part therefor.

80 3. A package as set forth in claim 1, characterized in that the container structure includes two tubular container members each having a closed end, and a tubular centering member therefor.

85 4. A package as set forth in claim 1, characterized in that the container structure includes two identical tubular container members each having a closed end, and a tubular centering member therefor.

90 5. A package as set forth in claim 1, characterized in that the container structure includes two tubular container members each having a closed end, and a tubular centering member therefor adapted to be arranged therewithin and having a lining of water proof material.

95 6. A package as set forth in claim 1, characterized in that the container structure includes two tubular container members each having one closed end and a tubular centering member therefor, the tubular portions of 100 said container members being of fibrous material and the closing end portions thereof being of sheet metal, said centering member being of fibrous material with a lining of water proof material.

105 7. A package as set forth in claim 1, characterized in that said tooth paste tube has a portion clamped between said spacing and supporting tube and the upper end of said 110 container structure.

115 8. A package as set forth in claim 1, characterized in that said tooth paste tube has an end portion of greater length than the diameter of said spacing and supporting tube, said tooth paste end portion lying above and in engagement with the upper end of said spacing and supporting tube.

120 9. A package as set forth in claim 1, characterized in that said tooth paste tube has 125

an end portion of greater length than the diameter of said spacing and supporting tube, said tooth paste end portion being clamped between the upper end of said spacing and supporting tube and the upper end of the container structure.

10. A package as set forth in claim 1, characterized in that the spacing and supporting tube is of less diameter than the container structure so that an annular chamber is provided therebetween, and in that a tooth brush is arranged in said chamber with its lower end resting on said bottle.

15. In testimony whereof I hereby affix my signature.

WILLIAM A. WEAVER.
